UNITED STATES PATENT OFFICE.

WILLIAM H. LOCKE, OF CANTON, PENNSYLVANIA.

SCROLL OF WATER-WHEELS.

Specification of Letters Patent No. 31,810, dated March 26, 1861.

To all whom it may concern:

Be it known that I, Wm. H. Locke, of Canton, in the county of Bradford and State of Pennsylvania, have invented an Improvement in Making Scrolls for Water-Wheels, and that the following is a full, clear, and exact description of the principle or character which distinguishes it from all other things before known and of the usual manner of making, modifying, and using the same, reference being had to the accompanying drawings, of which—

Figure 1 is a horizontal cross section through the scroll and wheel. Fig. 2 a side elevation of the scroll put together. Fig. 3 detached views of the scroll joint in perspective. Fig. 4 detached view in elevation of part of division A.

My invention consists in an improvement in making cast iron scrolls for reaction water wheels described and represented as follows.

The scroll is cast in two vertical semi-cylindrical divisions A and B. On division A there is cast a projecting wing piece e and in this piece a vertical opening i, between the division and the outer portion of the

wing piece which is formed into a cylindrical pillar n. On division B is cast an ear piece m which is curved as seen in section Fig. 1 so as to embrace the pillar n. When the two divisions are to be put together the ear piece is inserted within opening i and the edges x of the scroll divisions being brought together they are held firmly by the joint formed by m and i and the clasp hooks t t which are on the top and bottom of the scroll. The peculiar joint made by ear pieces m and opening i being cast whole with the scroll divisions, makes a strong and very economical fastening, and although I do not confine myself to the clasp hooks as the means of locking the divisions together, yet if they are made to draw a little on the pins s they are very efficient.

What I claim is—

Casting the joint consisting of the ear piece m opening i and pillar n entire with the divisions of the scroll as set forth.

WM. H. LOCKE.
